A. CRICK.
SIGNAL FLAG FOR TAXICABS.
APPLICATION FILED JUNE 2, 1920.

1,347,210.

Patented July 20, 1920.

INVENTOR:
Arthur Crick
By Wallace White
ATTY.

UNITED STATES PATENT OFFICE.

ARTHUR CRICK, OF BRISTOL, ENGLAND, ASSIGNOR TO HUGH DENHAM SWEETLAND
AND ALBERT JAMES OWEN, BOTH OF BRISTOL, ENGLAND.

SIGNAL-FLAG FOR TAXICABS.

1,347,210.

Specification of Letters Patent. Patented July 20, 1920.

Application filed June 2, 1920. Serial No. 285,995.

To all whom it may concern:

Be it known that I, ARTHUR CRICK, of 186 Gloucester road, Bishopston, Bristol, in the county of Gloucester, England, a subject of the King of Great Britain and Ireland, have invented certain new and useful Improvements in and Relating to Signal-Flags for Taxicabs, of which the following is a specification.

10 This invention relates to signal flags of the type comprising a casing having a transparent front and containing an electric lamp for illuminating purposes, the circuit of which is closed when moved into the 15 "for hire" position. The object of this invention is to provide an improved flag of this type.

According to this invention I provide a gravity-operated switch contained within 20 the flag which closes or opens the switch when moved from one position to the other.

Referring to the accompanying drawings:

Figure 1 is a front view of the "flag" as 25 raised. It becomes illuminated by the act of raising.

Fig. 2 is a front view with the display front transparent panel omitted.

Fig. 3 is a section on the line $\alpha\alpha$, Fig. 1. 30 Fig. 4 is a vertical section on the line $\gamma\gamma$, Fig. 3.

Fig. 5 shows the flag as lowered to "engaged" position. The front panel is shown as broken away toward one end of the case.

35 A flag as made in accordance with this invention consists of a case 1 in which is contained an electric lamp 2, of the bulb type, and a device for making and breaking the lamp circuit. The ends, back and top 40 and bottom of the case are of sheet steel or other suitable metal. The front 3 is a pane of glass or other suitable transparent substance. It is suitably colored as, for example, green or red. The usual words 45 "For hire" are borne on the transparent front. The front panel 3 is adapted to be slid into place from one end thereof and is readily withdrawn for giving access to the interior of the case. The device is characterized by a gravity-operated switch contained 50 within the flag which closes or opens the switch when moved from one position to the other.

The terminals 4 and 5 of the lamp wires 55 stand each on separate contact blades 6 and

7 of gun metal or other suitable metal below which is an insulating pad 8. At the opposite end of the case to that at which the terminals 4 and 5 are situated is located a chamber 9 in which is a weight 10 which 60 is free to slide lengthwise in the chamber 9 which is closed at top and open below. The blade 6 lies throughout its length on the pad 8 and does not rise from it. The blade 6 lies in part under the blade 7 which latter is normally, that is to say, when the flag is in the lowered position, maintained by its own resiliency raised out of contact with the under blade 6. Both blades extend to below the open end of the chamber 70 9.

The case is secured to a pole 11 which is of the usual kind and pivotal for raising and lowering the flag as ordinarily. A convenient way of attaching the lantern is 75 by sliding it on to an existing plate flag 12 as shown in Figs. 3 and 4 of the drawings.

When the flag is in the raised position, as shown in Figs. 1 and 2, the weight 10 in the chamber 9 holds down the blade 7 in contact with the blade 6. The electric circuit through the lamp is established and the flag is thus illuminated showing that the vehicle is disengaged.

The act of turning the flag to the lowered 85 position causes the weight 10 to retire into the chamber 9. The blade 7 rebounds out of contact with the blade 6, the electrical circuit is broken and the lamp extinguished. This position is shown in Fig. 5.

90 By means of a switch in the leads to the lamp and placed in a position convenient for operation by the driver of the vehicle, supply of current to the flag is cut off in daytime and at such other times as desired.

95 My invention is applicable to "hackney" vehicles generally with or without meters.

What I claim and desire to secure by Letters Patent is:—

1. In a device of the kind described, the 100 combination with a hollow signal flag; of an electric lamp mounted within said flag, an open electric circuit whereto said lamp is connected, said circuit including normally spaced contacts, gravity means, with- 105 in said flag engageable in one position of the flag with one of said contacts to close the same on the remaining contact, and means to pivotally support said flag.

2. In a device of the kind described, a 110

lantern hire-flag comprising a case, an electric lamp therein, conductors for supplying the lamp with current, terminals for the conductors, a fixed contact blade in contact at one end with one lamp terminal, a spring contact blade in contact at one end with the other lamp terminal and arranged over a portion of the fixed contact blade, and a weight arranged to press the other end of the spring contact blade into contact with

the other end of the fixed contact blade, to close the lamp circuit when the hire-flag is in the position indicating "For hire", and to automatically release the said spring contact blade to allow this to open the lamp circuit when the hire-flag is moved out of the said position. ¹⁵

In testimony whereof I have signed my name to this specification.

ARTHUR CRICK.
